FREE-PISTON COMPRESSOR

Erich Anton Wachsmuth, Frankfurt am Main
Fechenheim, Germany

Application February 18, 1952, Serial No. 272,019

Claims priority, application Germany March 28, 1951

15 Claims. (Cl. 230—56)

This invention relates to two-cylinder, free-piston engine-compressor assemblages, and more particularly to such engine-compressors in which the engines are of the internal combustion (e. g. diesel) type and the assemblage of twin construction.

From a principal aspect, the invention is characterized by an arrangement of two opposed-piston systems, having their axes parallel and working in counter-stroke relation to each other (i. e. each making its particular strokes while the other is making its opposite strokes), the counter-stroke relation being effected and maintained by arrangements, such as double-armed rockers (levers pivoted between their ends) connecting the pistons in pairs, and said coupling arrangements being synchronized by suitable means, such as, advantageously, but without limitation thereto, mutually engaged toothed segments.

In a preferred embodiment, in which two motor-compressor systems work in counter-stroke relation, the energy required to effect compression in one motor cylinder is furnished directly from the energy produced during the working stroke in the corresponding cylinder. Accordingly, there will not be required, with such a construction, the measures heretofore functionally necessary with familiar free-piston machines for the pneumatic accumulation of energy for performing the work of compression in the motor—particularly the large clearance volume of the compressor cylinder, as well also as cushioning spaces (accumulators) for the storage of energy, which characterize free-piston machines. Thereby, machines constructed in accordance with the invention obtain an unusually favorable ratio, for a free-piston machine, between suction stroke and stroke-volume, whereby the already favorable cost of construction of known free-piston machines is still further improved. By the elimination of special pneumatic cushioning means, particularly the thermodynamic, but also the mechanical, efficiency (a thicker diagram is obtained) is improved and thereby the economy of such machines.

The two motor-compressor systems of a machine constructed according to an illustrative embodiment of the present invention, considered individually, are very similar in their construction to conventional free-piston compressors. Centrally, between the compressor cylinders, which lie to the outside, and axially in line with the compressor cylinders, lies the motor cylinder, which is open at both ends. Two differential pistons, whose small piston portions are associated with the motor cylinder and whose larger piston portions are associated with the compressor cylinders, convert, without the intermediation of any special transmission, the work of the motor of each system into the work of compression. In contrast with conventional constructions, in which the energy necessary to effect compression in the motor must be secured from the energy provided by the reexpansion of the air remaining in the clearance volume of the compressor (by reason of which fact the clearance volume must be maintained substantially larger than is customary and desirable in

2

ordinary compressors), with the foregoing construction—as a result of the double-armed rocker coupling or the like—the work done during the outward stroke in one cylinder always and directly furnishes the energy needed for the compression of the charge in the other. Thus, there is here eliminated the necessity of a pneumatic accumulation of energy to provide for the work of compression in the motor.

Furthermore, with a free-piston engine constructed according to the present invention, the ratio between the working stroke and the stroke-volume can be maintained of the same order of magnitude as with normal crank compressors. From this there results also a considerable improvement in overall efficiency in comparison with the usual crankshaft arrangements, compared with which, as many experiments confirm, the conventional free-piston machine, despite elimination of the crank transmission, is no better.

In the accompanying drawings, in which for purposes of illustration two illustrative embodiments of the invention are shown:

Fig. 1 is a diagrammatic view, in central longitudinal section, with parts in elevation, through a motor-compressor in which the invention is incorporated.

Fig. 2 is a similar view, with parts omitted, of a somewhat modified motor-compressor in which the invention is incorporated.

Fig. 3 is a transverse section on the line 3—3 of Fig. 2, with parts not essential to the disclosure of the present invention omitted.

Referring to the drawings, and first to Figure 1, it will be noted that motor cylinders 1, 1' are provided. The axes of these cylinders are at least substantially parallel and they are supported by a frame F. In the motor cylinders 1, 1' there reciprocate in counter-stroke relation to each other two pistons 4, 5 and 4', 5' which control the scavenging slots 2, 2' and the exhaust slots 3, 3'. These four pistons, formed as differential pistons, are coupled in pairs (4 coupled with 4', and 5 coupled with 5') each pair by a double-armed rocker 6, 7 (otherwise stated, centrally pivoted levers), the first pair by the rocker 6, the second by the rocker 7, so that the outward travel (working stroke) of the pistons associated with the cylinder 1 corresponds with the inward (compression) stroke of the corresponding pistons in the cylinder 1', and vice versa. The two double-armed rockers 6 and 7 pivoted respectively at 8 and 9, carry fixed to them, toothed segments 10 and 11 which swing in the same direction as their respective rockers, and these toothed segments, through their mutual inter-engagement, prevent either of the piston systems from getting out of synchronism with the other. The toothed segments 10 and 11 are mutually engaged with each other at a common plane which cuts the central portions of the power or motor cylinders 1, 1' and is perpendicular to the axes of said cylinders. The rockers 6, 7 have their pivots closer to each other than the distance between the relatively remote ends of the compressor cylinders and have connections with the motor-compressor piston units with which they are respectively connected between the remote ends of the pistons of such piston units.

Each of the pistons, 4, 4' and 5, 5' supports for rocking movement therein a transverse pin P, and these pins have guideways 4^p, 4'^p, 5^p and 5'^p in them respectively. Each rocker 6, 7, is provided at its opposite ends with a portion (such portions severally designated 6^a, 6'^a and 7^a, 7'^a) slidably received in one of the guideways 4^p, 4'^p, 5^p, 5'^p.

Compressor cylinders 12, 13 and 12', 13' are disposed coaxial with the motor cylinders 1, 1' and are open at their ends toward the engine cylinders, but closed at their

outer ends by cylinder heads 14, 15 and 14', 15' which carry the suction and discharge valves 16, 17.

Two receivers 18 are shown. Beyond the discharge valves 17 there are connected pressure-retaining valves 19, one arranged between each discharge valve and a receiver 18. These pressure-retaining valves may be replaced by a single pressure retaining valve if a suitable conduit arrangement is provided. These pressure retaining valves, that is: spring-loaded valves, which permit the air to enter the receiver 18 only when it exceeds the designed (rated) pressure of the compressor, are necessary with the machine operating without the possibility of energy storage, in order to enable the machine to be satisfactorily started and maintained in operation independent of the pressure in the receiver. Immediately before starting the unit, the spaces 21 between the discharge valve and the pressure-maintaining valve, which spaces are connected with each other through an equalization line 20, are, for example by means of a small hand pump, pumped up to the rated pressure, so that at the compressor side normal operating conditions are already present when the first stroke of the machine takes place. Actual starting desirably is effected through the shooting apart of the pistons 4, 5 which have been brought together into their extreme inner positions in the starting cylinder 1. A small cartridge, provided with a small powder charge, and readily inserted in a suitable chamber 22, communicating with the space 23 between the pistons of the motor cylinder 1, when said pistons are in their most closely adjacent positions, serves to effect the shooting, the powder charge of the cartridge being ignited by a spring bolt striking upon its percussive cap. The energy of the powder charge is so determined that it shall be equal to the energy which is available during full load operation for forcing the pistons apart. The pistons 4 and 5, driven outwardly by the powder gases, thereupon provide, as in normal operation, the energy needed for effecting compression in the cylinder 1' and the necessary useful work in that they compress the air which was sucked into the compressor cylinders 12 and 13 upon movement of the pistons in the cylinder 1 towards each other prior to starting and force the compressed air out. Upon the overrunning of the exhaust and inlet slots 3, 2 in the starting cylinder 1, that cylinder is scavenged and charged as during normal operation, and simultaneously the normal charge of combustible mixture is injected into the counter-cylinder 1', which has been exhausted by the motion transmitted from the rocker, and, upon the ignition of this mixture, the normal running condition of the motor is attained.

Figures 2 and 3 show a modified design of motor-compressor, and the modifications which are significant in connection with the present invention are the only ones which need be specifically mentioned. It will be observed that a pair of motor cylinders 31 and 31' are arranged with their axes parallel and that in the cylinder 31 there reciprocate the motor portions of pistons 34 and 35, while in the cylinder 31' the motor portions of other pistons 34' and 35' are reciprocable. The pistons are again differential pistons and they are connected for movement in counter-stroke relation in pairs, 34, 34' and 35, 35', as will shortly be described. The connections include double-armed rockers 36 and 37 which pivot on axes 38 and 39 respectively. The double-armed rockers are constructed with their arms separate and mounted upon and keyed against relative rotation with respect to a shaft 40 oscillatably supported in a frame F'. Keys K fix the relation of the arms to the shafts.

Considering the construction of the rocker 37 (they are similarly constructed) it will be noted that this is made up of an upper (as shown in the drawing) arm 41 and a lower arm 42, and between the hubs 41^h and 42^h of these arms there is arranged the hub portion 43 of an arm 44 which carries at its outer end a rack segment 45 which interengages with a similar oppositely facing rack segment associated with the rocker 36. The

hubs of the arms 41, 42 and 44 are secured together by bolts 45.

The outer ends of the arms 41 and 42 are designated 51 and 52, and the hubs 41^h and 42^h are offset from the planes of the outer ends 51, 52 of the arms 41 and 42, so that they may have the hub portion 43 of the arm 44 mounted between them and still have the outer ends 51, 52 of the arms in the central longitudinal planes of the cylinders 31 and 31'. The outer ends of each 10 arm are provided with bearings 54 surrounding pins 55 which are in turn supported in box elements 56 which are slidably arranged in guides 57 extending transversely to the several pistons and providing for guided movement of the boxes 56 transversely of the pistons as the latter reciprocate. It will be evident that as in the first 15 construction described, the pairs of pistons will be maintained in synchronism and the pistons 34, 35 will operate in counter-stroke relation with the pistons 34', 35' and the explanations of the advantages of the arrangement of Fig. 1 will all be applicable to the embodiment disclosed in Figs. 2 and 3.

The specific structural elements described, including the double-armed rockers and toothed segments for the coupling and synchronization of the piston systems selected for description are but representative of other constructional features which may be employed in the practice of the invention, which is not confined to the single-stage construction of compressor herein described, but also includes multi-stage compressors of the same type.

While there are in this application specifically described two forms which the invention may assume in practice, it will be understood that these are shown for purposes of illustration, and that the invention may be modified and embodied in various other forms without departing from its spirit or the scope of the appended claims.

What is claimed is:

1. Two-cylinder, free-piston compressor, characterized by the arrangement of two opposed-piston systems 40 arranged with their axes substantially parallel and working in counter-stroke, whose operation in counter-stroke is effected by coupling arrangements in the form of double-armed rockers oscillating on fixed axes and connecting the pistons in pairs, which coupling arrangements are synchronized by mutually engaged toothed segments one fixed to each rocker and each directly engaged with the other.

2. In combination, two two-piston, free-piston compressors having their axial lines substantially parallel, and means for effecting operation of the pistons of said compressors in counter-stroke relation and maintaining synchronization between them including a pair of double-armed rockers connecting the pistons of said systems in pairs, said double-armed rockers having mutually engaged toothed segments secured to them and having the arcs of their respective pitch circles struck from the axes of rocker oscillation and their mesh line in a plane midway between said rockers and perpendicular to the axial lines of said compressors.

3. In an internal combustion, free-piston motor-compressor, in combination, coaxial motor and compressor cylinders respectively containing motor and compressor pistons which form a pair, other coaxial motor and compressor cylinders containing other motor and compressor pistons which form another pair, said first mentioned motor and compressor cylinders arranged with their axes parallel to the axes of said second mentioned motor and compressor cylinders, and means for connecting the piston pairs contained in said first and second mentioned coaxial motor and compressor cylinders to cause them to move in counter-stroke relation to each other including a lever pivotable upon a fixed axis between the cylinders in which said corresponding piston pairs are contained, said axis being disposed between the ends of said cylinders and 60 said lever having its opposite ends slidably and pivotally

connected with said piston pairs at points between the opposite ends of each of the latter.

4. A motor-compressor as defined in claim 3, in which each end of said lever has a sliding and rocking connection with a piston pair alternately transmitting movement to and deriving movement from the latter, and said piston pairs being hollow and housing said connections in their respective interiors.

5. A motor-compressor of the type described comprising in combination two power cylinders disposed side by side and each having at each of its opposite ends a compressor cylinder, two pairs of opposed motor pistons, one pair reciprocable in each of said power cylinders, a compressor piston movable with each motor piston and reciprocable in a compressor cylinder, two levers pivoted on fixed axes and each operatively connected at one end with a motor piston and a compressor piston, and means arranged wholly between the most widely spaced points in said compressor cylinders for connecting said levers to swing mutually oppositely with respect to each other, in synchronism, said last mentioned means comprising arms, one connected to each lever adjacent the center of the latter, and arcuate racks one on each of said arms meshing directly with each other.

6. A motor-compressor comprising motor and compressor cylinders, pairs of pistons adapted to reciprocate in said cylinders, and means connecting said pairs of pistons to force the pistons of one pair to approach each other as those of the other pair move apart including a pair of rockers and arcuate gear means rocking with said rockers and engaged with each other, said rockers and said arcuate gear means rocking therewith rocking on stationary axes of which the distance apart is equal to the diameter of the pitch circle of either of said arcuate gear means.

7. In a motor-compressor consisting of at least two opposed-piston motor compressor units each having motor and compressor pistons and motor and compressor cylinders, means connecting the pistons of said units in such a manner that, on its working stroke, the motor piston of each unit moves its own compressor piston to effect compression and simultaneously causes the compression stroke of the corresponding motor piston and the suction stroke of the corresponding compressor piston of the other unit, said connecting means including rockers swingable on fixed axes in planes perpendicular to the axes of said cylinders and at least substantially midway between the ends of the strokes of the pistons which they connect, and means in the space between said connecting means connecting the latter whereby the motor and compressor pistons at the opposite ends of each unit are maintained in synchronism with each other.

8. In a motor-compressor as defined in claim 7, the arrangement in which the means in the space between the connecting means connecting the latter comprises arcuate members swinging at like angular rates with the rockers and disposed in a zone transverse to said motor-compressor adjacent the longitudinal center thereof.

9. A motor-compressor of the type described comprising, in combination, two power cylinders arranged parallel with each other and with their central portions cut by a common plane perpendicular to their axes, two pairs of opposed motor pistons adapted to reciprocate in said cylinders respectively, each motor piston having fixed to its outer end a compressor piston, two pairs of compressor cylinders each pair having between its cylinders one of the first mentioned cylinders and adapted to receive the compressor pistons fixed to the outer ends of the pistons of the first mentioned cylinders respectively, means for connecting one motor piston of one pair to the corresponding motor piston of the other pair to cause them to move simultaneously in mutually opposite directions, means for connecting the other motor piston of said one pair with the corresponding motor piston of said other pair to cause them to move simultaneously in mutually

opposite directions, and means including elements each movable relative to the other and mutually engaging with each other at said common plane for connecting said connecting means to cause the pistons of each pair to move in synchronism with each other.

5 10 15 20 25 30 35 40 45 50 55 60 65 70 75

10. A motor-compressor of the type described comprising, in combination, first aligned motor and compressor cylinders, second aligned motor and compressor cylinders arranged parallel to the first cylinders, a piston structure including motor and compressor pistons reciprocable in said first motor and compressor cylinders, a piston structure including motor and compressor pistons reciprocable in said second motor and compressor cylinders, a double-armed rocker pivoted on a stationary axis midway between said first and said second motor and compressor cylinders, and connections between each arm of said rocker and one of said piston structures including slidable and rockable connections between them.

11. A motor-compressor of the type described comprising, in combination, first aligned motor and compressor cylinders, second aligned motor and compressor cylinders arranged parallel to the first cylinders, a piston structure including motor and compressor pistons reciprocable in said first motor and compressor cylinders, a piston structure including motor and compressor pistons reciprocable in said second motor and compressor cylinders, a double-armed rocker pivoted on an axis between said first and said second motor and compressor cylinders, and connections between each arm of said rocker and one of said piston structures including a block guided on said piston structure for sliding movement transverse to the axis of said structure and a pivotal connection between said block and said arm.

12. A motor-compressor of the type described comprising, in combination, first aligned motor and compressor cylinders, second aligned motor and compressor cylinders arranged parallel to the first cylinders, a piston structure including motor and compressor pistons reciprocable in said first motor and compressor cylinders, a piston structure including motor and compressor pistons reciprocable in said second motor and compressor cylinders, a double-armed rocker pivoted on an axis between said first and said second motor and compressor cylinders, and connections between each arm of said rocker and one of said piston structures including an element having a sliding connection with one of said rocker arm and piston structure and a rocking connection with the other.

13. A motor-compressor of the type described comprising in combination two power cylinders disposed side by side and each having at each of its opposite ends a compressor cylinder, two pairs of opposed motor pistons, one pair reciprocable in each of said power cylinders, a compressor piston movable with each motor piston and reciprocable in a compressor cylinder, two levers pivoted on fixed axes and each operatively connected at one end with a motor piston and a compressor piston, and means arranged wholly between the most widely spaced points in said compressor cylinders for connecting said levers to swing mutually oppositely with respect to each other, in synchronism, said last mentioned means comprising arms, one connected to each lever adjacent the center of the latter and each having at its end remote from its lever a connection with the other comprising directly engaged elements between which a connection is maintained during swinging of said levers.

14. A motor-compressor of the type described comprising, in combination, two power cylinders arranged parallel with each other and with their central portions cut by a common plane perpendicular to their axes, two pairs of opposed motor pistons adapted to reciprocate in said cylinders respectively, each motor piston having fixed to its outer end a compressor piston which forms therewith a motor-compressor piston unit, whereby there are two pairs of motor-compressor piston units, two pairs of compressor cylinders each pair having between its cylinders

one of the first mentioned cylinders and adapted to receive the compressor pistons fixed to outer ends of the pistons of the first mentioned cylinders respectively, means for connecting one motor-compressor piston unit of one pair to the corresponding motor-compressor piston unit of the other pair to cause them to move simultaneously in mutually opposite directions, said means including a rocker pivoted between its ends and having connections with the motor-compressor piston units between the remote ends of the pistons of the latter, means for connecting the other motor-compressor piston unit of said one pair with the corresponding motor-compressor piston unit of said other pair to cause them to move simultaneously in mutually opposite directions, said last mentioned means including a rocker pivoted between its ends and having connections with the motor-compressor piston units between the remote ends of the pistons of the latter, and means for connecting said connecting means to cause the motor-compressor piston units of each pair to move in synchronism with each other, said rockers having their pivots closer to each other than the relatively remote ends of the compressor cylinders.

15. In a motor-compressor consisting of at least two opposed-piston motor-compressor units each having motor and compressor pistons and motor and compressor cylin- 20 25

ders, means connecting the pistons of said units in such a manner that, on its working stroke, each motor piston of one unit moves its own compressor piston to effect compression and simultaneously causes the compression stroke of the corresponding motor piston and the suction stroke of the corresponding compressor piston of the other unit, said connecting means including rockers swingable on fixed axes in planes perpendicular to the axes of said cylinders and between the remote ends of the strokes of the pistons which they connect, and means bridging the space between said connecting means connecting the latter whereby the motor and compressor pistons at the opposite ends of each unit are maintained in synchronism with each other.
